UNITED STATES PATENT OFFICE.

ANTHONY A. NIEBERDING, OF BROOKPARK, OHIO.

DESIGN FOR A HEATER.

Application filed January 26, 1927. Serial No. 20,510. Term of patent 7 years.

To all whom it may concern:

Be it known that I, ANTHONY A. NIEBERDING, a citizen of the United States, residing at Brookpark, in the county of Cuyahoga and State of Ohio, have invented a new, original, and ornamental Design for a Heater, of which the following is a specification, reference being had to the accompanying drawing, forming part hereof, wherein—

Fig. 1 is a front elevation, and Fig. 2 a side elevation, of a heater showing my new design.

I claim:

The ornamental design for a heater as shown.

ANTHONY A. NIEBERDING.
